CLAIM

The ornamental design for a simulator frame, as shown and described.

DESCRIPTION

FIG. 1 is a rear upper perspective view of a simulator frame in a first configuration;

FIG. 2 is a rear lower perspective view of a simulator frame in a first configuration;

FIG. 3 is a front upper perspective view of a simulator frame in a first configuration;

FIG. 4 is a front lower perspective view of a simulator frame in a first configuration;

FIG. 5 is a first side view of a simulator frame in a first configuration;

FIG. 6 is a front view of a simulator frame in a first configuration;

FIG. 7 is a rear view of a simulator frame in a first configuration;

FIG. 8 is a second side view of a simulator frame in a first configuration;

FIG. 9 is a top view of a simulator frame in a first configuration;

FIG. 10 is a bottom view of a simulator frame in a first configuration;

FIG. 11 is a rear upper perspective view of a simulator frame in a second configuration;

FIG. 12 is a rear lower perspective view of a simulator frame in a second configuration;

FIG. 13 is a front upper perspective view of a simulator frame in a second configuration;

(Continued)

FIG. 14 is a front lower perspective view of a simulator frame in a second configuration;
 FIG. 15 is a first side view of a simulator frame in a second configuration;
 FIG. 16 is a front view of a simulator frame in a second configuration;
 FIG. 17 is a rear view of a simulator frame in a second configuration;
 FIG. 18 is a second side view of a simulator frame in a second configuration;
 FIG. 19 is a top view of a simulator frame in a second configuration;
 FIG. 20 is a bottom view of a simulator frame in a second configuration;
 FIG. 21 is a rear upper perspective view of a simulator frame in a third configuration with straps removed;
 FIG. 22 is a rear lower perspective view of a simulator frame in a third configuration with straps removed;
 FIG. 23 is a front upper perspective view of a simulator frame in a third configuration with straps removed;
 FIG. 24 is a first side view of a simulator frame in a third configuration with straps removed;
 FIG. 25 is a front view of a simulator frame in a third configuration with straps removed;
 FIG. 26 is a rear view of a simulator frame in a third configuration with straps removed;
 FIG. 27 is a second side view of a simulator frame in a third configuration;
 FIG. 28 is a top view of a simulator frame in a third configuration with straps removed; and,
 FIG. 29 is a bottom view of a simulator frame in a third configuration with straps removed.

The broken lines in the drawings depict portions of the simulator frame that form no part of the claimed design.
